UNITED STATES PATENT OFFICE.

CHARLES EDWIN KELLER, OF LOS ANGELES, CALIFORNIA.

BOOT-HEEL.

SPECIFICATION forming part of Letters Patent No. 659,073, dated October 2, 1900.

Application filed February 5, 1900. Serial No. 4,083. (No model.)

To all whom it may concern:

Be it known that I, CHARLES EDWIN KELLER, a citizen of the United States, and a resident of Los Angeles, in the county of Los Angeles and State of California, have invented 5 new and useful Improvements in Boot-Heels, of which the following is a full, clear, and exact description.

The purpose of this invention is to provide 10 a yielding heel for boots and shoes, and I attain this end by providing a rubber pad with a metallic spring attached, thus presenting a more durable device than one constructed entirely of rubber and yet insuring an effective 15 cushion to the tread of the person using the device.

This specification is the disclosure of one 20 form of my invention, while the claims define the actual scope thereof.

Reference is to be had to the accompanying 25 drawings, forming a part of this specification, in which similar characters of reference indicate corresponding parts in all the views.

Figure 1 is a perspective view illustrating 30 the device applied to a shoe. Fig. 2 is a sectional view on the line 2 2 of Fig. 1. Fig. 3 is a bottom view of the spring. Fig. 4 is a bottom view of the rubber pad, and Fig. 5 is a top view thereof.

The heel of the shoe has a recess *a* cut in 35 the bottom thereof of the form shown in Fig. 1, and to the top wall of this recess is secured by fastening devices *b* of any desired construction the metallic spring, which comprises a body plate *c*, through which the fastening devices *b* are passed, and two spring prongs or fingers *c'*, which are projected from 40 the inner end of the body-plate *c* downwardly and then rearwardly parallel with the body-plate. The rubber cushion-plate *d* has a cavity *d'* formed in its top face, in which is set the body *c* of the spring. The cushion-plate *d* also has openings *d''* formed in its inner end, through which the prongs *c'* are respectively

passed, and the bottom face of the plate *d* is 45 formed with two grooves *d''*, in which the prongs *c'* respectively lie. It will thus be seen that the spring, being fastened securely to the heel, serves to hold the cushion-plate *d* in the recess *a* of the heel and that this arrangement provides an effective, yet thoroughly durable, cushion for the heel. The 50 spring prongs *c* cushion the tread as well as the plate *d*, and the spring-prongs hold the plate in place without the necessity of fastening devices passing through the plate, and at the same time they protect the plate from being cut or torn during the use of the device.

Having thus described my invention, I claim as new and desire to secure by Letters 55 Patent—

1. An attachment for the heels of boots and shoes, comprising a spring-prong adapted to be attached to the heel, and a cushion-plate 60 detachably embraced by the prong. 65

2. An attachment for the heels of boots and shoes, comprising a spring having a body-plate attached to the heel, a spring-prong projecting downwardly and then rearwardly parallel with the body-plate, and a yielding cushion-plate held between the body-plate and 70 the prong.

3. An attachment for the heels of boots and shoes, the attachment comprising a spring having a body-plate and one or more spring 75 prongs carried thereon and extending parallel therewith, and a yielding cushion-plate having openings formed therein through which the prongs are passed, the cushion-plate also having grooves for the reception of 80 the prongs.

In testimony whereof I have signed my name to this specification in the presence of two subscribing witnesses.

CHARLES EDWIN KELLER.
